United States Patent Office

Des. 212,459
Patented Oct. 22, 1968

212,459

JAR OR SIMILAR ARTICLE

Floyd E. Pettengill, Lancaster, Ohio, assignor to Anchor
Hocking Glass Corporation, Lancaster, Ohio, a corporation of Delaware

Filed Sept. 23, 1966, Ser. No. 3,990

Term of patent 14 years

(Cl. D9—92)

Fig. 1.

Fig. 2.

FIG. 1 is an elevational view of a jar or similar article showing my new design; and

FIG. 2 is a sectional view taken along line 2—2 of FIG. 1.

The dominant features of my design reside in the portions shown in full lines.

I claim:

The ornamental design for a jar or similar article, substantially as shown and described.
